SAFETY DEVICE FOR STAMPING PRESSES
AND THE LIKE

Emil Sandel, St. Louis, Mo.

Application November 8, 1940, Serial No. 364,911

11 Claims. (Cl. 74—614)

This invention relates to power driven stamping presses and the like, and, has for its object the provision of a safety guard therefor disposed in front of the work space of the press, where dies and the like are positioned, to protect the operator's hand and body against accidents during the descent of the press ram.

A further object of the invention resides in the provision of means for adjusting the safety guard device to meet the requirements of various sizes of stamping presses.

A further object of the invention resides in the provision of means for controlling the movement of the safety device to safety position within the first quarter revolution of the crank-shaft of the press.

With the above and other objects in view, the invention consists in the novel features of construction, arrangement and combination of parts hereinafter more fully described and finally pointed out in the claims hereto appended.

Referring to the accompanying drawings:

Fig. 1 is a side elevation of a stamping press, or the like equipped with a safety curtain guard device embodying the features of my invention, the device being shown in full lines in non-safety or inoperative position, in dotted lines in two safety positions, and also in dotted lines in an elevated inoperative position such, as when dies are being changed, or for other purposes.

Fig. 2 is a top plan view of a press equipped with my safety device and showing the device as corresponding to the lowered full line non-safety position in Fig. 1.

Fig. 3 is a perspective view of the safety device as it appears in its safety position when the crank-shaft has turned approximately one-fourth revolution to effect initial descent of the press ram, and illustrating an operator's arm and hand, which has been moved out of danger position by the device even against the operator's will before the ram has fully descended.

In the drawings, I have illustrated, more or less conventionally, a power stamping press or the like designed, generally as A, and which includes suitable side frame members 1 and 1'; the operator's table 2, the crank-shaft 3, and the plunger or ram 4, the reciprocating movement of which is controlled by rotation of the crank-shaft 3 in the usual well known manner.

In cooperation with the press, I employ a pair of lever arms designated, generally as 5 and 5'. The lever arms 5 and 5', as illustrated, each consists of a rear socket member 6 having a bearing head 7, a rod 8, a front socket member 9 having

a forward head portion 10. The forward or free ends of the rods 8 are preferably fixedly secured to the front socket member 9.

The rear ends of the rods 8 are telescopically connected with the rear socket members 6. The rear socket members 6 each have their wall longitudinally slit, as at 11, for a suitable distance of the length thereof and they are each provided with a pair of ears 12 on opposite sides of the slits 11. The ears 12 are adapted to receive suitable fastening devices such, for instance, as suitable screws 13 to clamp the rear ends of the rods 8 against longitudinal displacement within the socket members 6. This arrangement allows for the lengthening and shortening of the lever arms 5 and 5' to accommodate presses of different dimensions of operator's tables from front to rear thereof.

The head portions 7 of each rear socket member 6 is provided with an opening 14 so that the head portions 7 can be mounted upon pivot pins 15 projecting from suitable supporting members 16, which are suitably secured to the press frame members 1 and 1', such, for instance as by means of screws 16'. The lever arms 5 and 5' project forwardly and downwardly from the pivot pins 15 to a point preferably, although not necessarily, in advance of the forward edge of the operator's table 2.

A suitable cross-shaft 17 connects the head portions 10 of the front socket members 9 and it is suitably held against rotation in openings 10' in said head portions.

A suitable roller guard member 18 is mounted for rotation, in either direction, on the cross-shaft 17. The roller 18 is provided at one end with a longitudinal bore 19 of suitable dimensions and it is closed at its open end by means of a suitable cap member 20 which is suitably secured to the end of the roller and which is provided with an opening 21 through which one end of the shaft 17 passes. A suitable coiled spring 22 encircles the shaft 17 within the bore 19 and one end of the spring 22 is suitably anchored to the shaft 17, as at 17' and the other end is suitably secured to the roller, as at 21'.

A suitable flexible curtain guard 23 is suitably secured at one end thereof to the roller guard member 18 and is normally wound a number of times around the roller guard member 18. The opposite or lower edge of the curtain guard 23, which can be of suitable heavy fabric, flexible leather, or other suitable flexible material, is provided with a suitable reinforcing member 24 having a plurality of fastener receiving openings 25,

Operation

A plurality of suitable hook shaped, or equivalent fasteners 26 are suitably secured to the front face of the press adjacent the operator's table 2, and are adapted to pass through the curtain guard openings 25 to support the lower end of the guard curtain.

The means for actuating the lever arms for raising the roller guard member and stretching the guard curtain in front of the work space of the press, comprises, in part, a suitable wheel like member 27, or its equivalent, which is suitably secured to one end of the crank-shaft 3, such for instance, as by screws 28, so as to rotate therewith, a member designated, generally, as 29, which is slidably adjustable upon one of the lever arm rods 8, and a connecting rod designated, generally, as 30.

The slidably adjustable member 29 includes a body portion 31 provided with an opening 31' through which the rod 8 of lever arm 5 passes. The wall of the body portion 31 is split, as at 32, and the wall is provided with a fastening device such, as a screw 33, for clamping the body portion 31 to the rod 6 in the desired adjusted position. Integral with the outer end of the body portion 31 is a body portion 34 having an elongated vertically disposed passage 35, and it has its lower face provided with a suitable recess 36 serving as a semi-circular bearing.

The connecting rod 30 includes a suitable L-shaped upper section 37 and a lower rod like section 38, the upper end of which is suitably connected with the lower end of the upper section 37. The upper end portion of the upper section 37 is pivoted eccentrically, as at 39, to the wheel like member 27 secured to the end of the crank shaft 3, and, the lower end portion of the rod like section 38, which is provided with screw-threads 40, passes downwardly through the passage 35.

The lower end of the screw-threaded portion of the rod section 38 is provided with a horizontally disposed, internally screw-threaded stop member 41 to limit downwardly movement of the lever arms 5 and 5', which is normally seated in the semi-circular recessed bearing surface of the body portion 34 of the member 29 adjustably mounted on the rod 8 of the lever arm 5. The stop member 41 serves to raise the lever arms 5 and 5' and cause the roller guard member to be elevated and the guard curtain stretched to safety positions during the first quarter revolution of the crank-shaft 3, as shown in dotted lines designated, generally as B, in Fig. 1, and to final safety positions before the crank-shaft has moved one-half revolution, as shown in dotted lines designated, generally as C, in Fig. 1.

A depending chain or equivalent member 42 is carried by the press frame member 1', and a suitable hook-shaped member 43 is carried by the socket member 6 of the lever arm 5'. This arrangement of parts enables lever arms 5 and 5', roller guard member 18 to raise to an elevated inoperative position, designated D, as illustrated in dotted lines in Fig. 1, when it is desired to change dies, or for repairs, or for any other purpose. However, before the lever arms 5 and 5' are moved into the dotted line position designated D, in Fig. 1, the lower end of the flexible curtain guard is detached from the hooks 26 and the ends of the reinforcement member 24 will engage the lever arms 5 and 5' due to the action of the spring actuated roller 18 having a tendency to wind the curtain guard 23 upon the roller guard member 18.

When the guard roller 18 is in its lowermost full line position as shown in Figs. 1 and 2, it is in its normal, or neutral position, and the ram 4 is then in its uppermost position. When the crank-shaft 3 starts to revolve, the ram 4 starts to descend, and as the crank-shaft starts to revolve, clockwise, and by the time it has moved one-quarter turn, the lever arms 5 and 5' as well as the roller guard 18 has moved to the safety position shown in dotted lines B in Fig. 1, and the guard curtain 23 has been partly unwound therefrom and stretched in front of the work space on the operator's table 2. As illustrated in Fig. 3, should the operator be dilatory in removing his hand from the die which he is feeding, the guard roller 18 will elevate the operator's arm, and roll the same away from moving parts of the press to the safety position shown in Fig. 2, prior to the ram reaching its lowermost position and the roller guard reaching the position shown in dotted lines designated C, in Fig. 1, which is the extreme elevated position of the lever arms and the guard roller.

It is generally assumed, and usually a fact, that safety devices designated to protect the stamping press operator handicaps the efficiency of the operation of the press to some degree, dependent upon the type of press, upright or inclinable, correctly designated dies, etc., but it has been actually found to be a fact that a press provided with my safety device will not handicap the efficiency of the operation but actually increase the efficiency thereof thereby increasing production, plus the safety feature of the device.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

50. 1. In a stamping press having a crank-shaft and an operator's table disposed below and in advance of the crank-shaft, a safety device of the shade roller type including a rotatable guard member, said member being spring actuated in one direction of rotation, a flexible curtain guard wound upon the guard member, means for anchoring one end of the curtain guard to the frame of the press adjacent the operator's table, and means cooperating with the rotatable guard member and the crank-shaft operable during the first quarter revolution of the crank-shaft to elevate and simultaneously therewith rotate the guard member and thereby lengthen the flexible curtain guard between the point of anchorage thereof and the rotatable guard member and immediately in front of the work space above the operator's table.
55. 2. In a stamping press having a crank-shaft and an operator's table disposed below and in advance of the crank-shaft, a rotatable safety guard member normally disposed adjacent the front top edge of the operator's table, a flexible curtain guard cooperating with the guard member, pivoted members cooperating with and ac-
60. 3. In a stamping press having a crank-shaft and an operator's table disposed below and in advance of the crank-shaft, a rotatable safety guard member normally disposed adjacent the front top edge of the operator's table, a flexible curtain guard cooperating with the guard member, pivoted members cooperating with and ac-
65. 4. In a stamping press having a crank-shaft and an operator's table disposed below and in advance of the crank-shaft, a rotatable safety guard member normally disposed adjacent the front top edge of the operator's table, a flexible curtain guard cooperating with the guard member, pivoted members cooperating with and ac-
70. 5. In a stamping press having a crank-shaft and an operator's table disposed below and in advance of the crank-shaft, a rotatable safety guard member normally disposed adjacent the front top edge of the operator's table, a flexible curtain guard cooperating with the guard member, pivoted members cooperating with and ac-
75. 6. In a stamping press having a crank-shaft and an operator's table disposed below and in advance of the crank-shaft, a rotatable safety guard member normally disposed adjacent the front top edge of the operator's table, a flexible curtain guard cooperating with the guard member, pivoted members cooperating with and ac-

tuated by the crank-shaft to move the guard member upwardly and unwinding the curtain guard wound thereon to lengthen the same immediately in front of the work space above the operator's table during the first quarter revolution of the crank-shaft, and said rotatable guard member being spring rotated to rewind the curtain guard upon the rotatable guard member and to return the member to starting position after the first half revolution of the crank-shaft.

3. A safety guard for stamping presses having a crank-shaft and an operator's table, co-operating guard members disposed in advance of the work space above operator's table, one of the guard members being rotatable and arcuately elevatable, and the other guard member being flexible and windable upon and unwindable from the rotatable guard member during downward and upward movements, respectively, of the rotatable guard member, the said other guard member being anchored at its lower end to the press adjacent the front of the operator's table and adapted to be stretched upwardly directly in front of the work space during upward movement of the rotatable guard member.

4. In combination with a hand feed stamping press having a crank-shaft actuated ram and an operator's table, a pair of spaced lever arms pivoted at their rear ends to the frame of the press above the operator's table, means for adjusting the length of the lever arms, a guard roller mounted to rotate between the free forward ends of the lever arms, said roller being spring actuated in one direction of rotation, a flexible curtain guard windable upon and unwindable from the guard roller, means for anchoring the lower end of the guard curtain to the press adjacent the forward end of the operator's table, and means connecting one of the lever arms with the crank-shaft to effect upward movement of the guard roller to a safety position during the first quarter revolution of the crank-shaft and inoperative as to connection with its respective lever arm during downward movement of the lever arms.

5. A safety device for stamping presses and the like having a crank-shaft operated ram, comprising a roller like safety guard member, arcuately movable means for upwardly moving the guard member to a safety position in front of the work space of the press during one-half of the downward stroke of the ram, and means connecting the guard member with the front of the press below the work space to rotate the member during upward movement thereof to roll an operator's hand outwardly from danger position, if in such a position, within the first quarter turn of the crank-shaft.

6. A safety device for stamping presses and the like having a crank-shaft operated ram, comprising a horizontally disposed cylindrical safety guard member, means for rotatably supporting the roller in front of the work space of the press, means connecting the crank-shaft with said means for moving same upwardly to a safety position in front of the work space during one-half of the downward stroke of the ram, a flexible curtain connecting the guard member with the press in front of and below the work space to rotate the guard member in one direction during said movement of the ram and to roll an operator's hand from danger position, if in such a position, during the first quarter turn of the crank-shaft, and means for instantly returning

the safety guard to neutral position and rotate the guard member in an opposite direction just prior to completion of the first half revolution of the crank-shaft.

- 5 7. In combination with a hand feed stamping press having a crank-shaft actuated ram and an operator's table, of a guard member rotatably supported in advance of the operator's table, a guard curtain normally wound upon the guard roller, means for anchoring the lower end of the guard curtain to the press adjacent the front end of the operator's table, means for elevating and rotating the guard roller in one direction in front of and above the operator's table during the first quarter revolution of the crank-shaft and simultaneously therewith stretching the guard curtain in front of and above the work space over the operator's table, and means for rotating the guard roller in an opposite direction upon completion of the first half revolution of the crank-shaft for rewinding the guard curtain upon the guard roller and simultaneously therewith returning the guard roller to neutral position.
- 10 15 20 25 30 35 40 45 50 55 60 65 70 75 80 85 90 95
8. A stamping press having, in combination, a frame including an operator's table, a crank-shaft, and a reciprocable ram above the table with a work space between the table and the ram, a rotatable safety guard, operating means controlled by the crank-shaft during the first quarter revolution thereof to move the safety guard upwardly a predetermined distance from a neutral position adjacent the front edge of the operator's table, and means for simultaneously rotating the safety guard in a direction to roll an operator's arm outwardly from the work space when contacted by the safety guard, and means for instantly lowering the safety guard and simultaneously rotating the same in an opposite direction at the completion of one-half revolution of the crank-shaft.

9. A stamping press including an operator's table and a reciprocable ram, a safety guard member normally disposed adjacent the front edge of the table, operating means to move the guard member upwardly a predetermined distance during the first-half of the down stroke of the ram, means cooperating with the guard member to rotate the guard member in a direction to roll an operator's arm out of the danger zone above the operator's table should it be contacted by the guard member, and means for returning the guard member to neutral position after the full down stroke of the ram and rotating the guard member in a direction opposite to the first mentioned direction.

10. A stamping press having, in combination, a press frame including an operator's table, a crank-shaft, a ram actuated by the crank-shaft, a pair of longitudinally adjustable lever arms, means for pivotally connecting the rear ends of said arms to the side of the press frame a predetermined distance above the operator's table and to the rear thereof, a member connecting one of the lever arms with the crank-shaft, said member having an eccentric connection with the crank-shaft, a guard roller mounted for rotation between the forward ends of the lever arms, a guard curtain connecting the guard roller with the forward end of the press adjacent the operator's table, said guard roller being rotated clockwise upon upward movement of the lever arms, means for rotating the guard roller anti-clockwise and returning the roller and the lever arms to neutral position independent of the member

connecting the said one lever arm with the crank-shaft.

11. The method of protecting a stamping press operator from accidental injury to the feeding hand and to the body from flying pieces by elevating and rolling the operator's arm out of the danger zone, which comprises raising a rotatable guard member and simultaneously therewith unrolling and stretching a curtain guard immediately in front of the work space of the press during the first quarter revolution of the crank-shaft

of the press to elevate the operator's arm if struck by the guard member and progressively thereafter roll the operator's arm away from the work space, completing the upward movement of the guard member before the first one-half revolution of the crank-shaft, and instantly returning the guard member to starting position and simultaneously therewith rewinding the curtain guard independently of further movement of the crank-shaft.

10

EMIL SANDEL.
